(57) **CLAIM**

The ornamental design for a learning tower, as shown and described.

DESCRIPTION

FIG. 1 is a front, left, and top perspective view of a learning tower, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right and top perspective view thereof;

FIG. 9 is an enlarged view of the portion labeled "9" framed in FIG. 8;

FIG. 10 is a front, left, and top perspective view of the learning tower in an unfolded position; and,

FIG. 11 is a rear, right, top perspective view of the learning tower, thereof.

The broken lines shown in the drawings depict portions of the learning tower that form no part of the claimed design.
